UNITED STATES PATENT OFFICE

BERNHARD FOERSTER, OF PFORZHEIM, GERMANY

PROCESS FOR WORKING GUIDE SLEEVES FOR SPRING RINGS

Application filed January 20, 1931, Serial No. 509,966, and in Germany October 14, 1929.

This invention relates to a process for working guide sleeves for spring rings.

As is known spring rings are used as fastening means for ornamental chains of all kinds and also as connecting means for watch-key and similar chains. They consist essentially of three parts, namely the sleeve, bent ring-shape, the catch guided in this sleeve, and the catch spring pressing the catch continually into its locking position.

Spring rings are known with slotted or unslotted guide sleeves. The longitudinal slot provided in the slotted guide sleeves serves for guiding the shank of the catch button projecting through the slot on which the catch made of wire can be displaced against the action of the catch spring so that the ring gap in the sleeve bridged by the spring actuated catch opens.

In the mass production of a small object such as the guide sleeve, special difficulties are encountered in making a clean usable longitudinal slot. This should afford a good smooth guiding with suitable stop ends for the shank of the catch to be easily inserted in the guide sleeve. For this purpose it is essential that all kinds of burr are removed without expensive subsequent manual labor and further that the slot is of suitable form for inserting the catch spring and the catch.

This invention solves this problem in a very satisfactory manner, both from a technical as also from an economical point of view.

The new process consists in that the longitudinal slot of the guide sleeve is cut by a milling cutter, saw or the like and then finished by means of a like or similar tool the cutting edge of which is however moved in the opposite direction, that moreover the cutting surface visible from the outer side, produced by the cutting of the slot, and the burr-like edge existing on the edge of this latter are removed by means of tapered end mills, and at the same time a funnel-shaped insertion opening is produced for the catch spring and the catch.

The process is hereinafter described with reference to the accompanying drawings, in which:

Fig. 1 is a front elevation of a periodically

rotated revolving disc onto which the guide sleeves are deposited for working.

Fig. 2 is a top plan view of the revolving disc and of the working tools arranged on its circumference.

Figs. 3, 4 and 5 are each a top plan view of the first, second, third and fifth working point.

Fig. 6 is a top plan view partly in section of a spring sleeve ready for the introduction of the catch spring and of the catch pin.

Fig. 7 shows in front view the slot after the first and second operations.

Fig. 8 shows in front view the finished widened slot.

To bring the guide sleeves *i* to the first working point, that is in the example shown to the milling cutter *p*, they are each placed by hand or with the aid of a special feeding and depositing device in a ring-shaped depression *n*₁ of a revolving disc *n* which is intermittently rotated in known manner. By means of this disc the blanks are fed to the different working points. The guide sleeves *i* are deposited in such a manner that in all blanks the slot *i*₂ is situated at the proper position, that is shortly behind the gap *i*₁ in the sleeves. In order to prevent the blank *i* from changing its position in relation to the revolving disc *n* during the working, small retaining pins *n*₂, fitting exactly in the gaps of the sleeves, are provided in the depressions *n*₁. Moreover the blanks *i* are held in the working positions by means of counter holders *o*, which bear on the blanks when the revolving disc *n* is at a standstill.

These holders preferably have each a depression *o*₁, similar to the depressions *n*₁ in the revolving disc *n*, and exposing, also in a similar manner to the revolving disc *n*, so much surface of the blank *i* as is necessary for the unimpeded working thereof.

In the first working position shown on an enlarged scale in Fig. 3 the guide slot *i*₂ (Fig. 6) for the shank of the spring knob is milled. This is effected by means of a disc cutter *p* which rotates for example in the direction *B*. Experience has shown that when milling the slot *i*₂ a burr *i*₃ always remains extending from end to end of the slot. Hitherto the

removal of this burr has been laboriously effected by hand.

At the second working point shown on an enlarged scale in Fig. 4 a second disc cutter 5 *g* engages in the slot *i*₂ provided with the burr *i*₃. This cutter rotates in the direction D, which is opposite to the direction B. It has been found that the slot burr *i*₃ which hitherto yielded to the cutter *p* and remained 10 adhering to the edge of the slot, is broken up and completely removed.

Owing to the milling of the slot *i*₂ with the cutters *p* and *g* sloping cut faces *i*₄ visible from the outer side (Figs. 4 and 7) are produced 15 at the ends of the slots, which faces impede the insertion both of the catch spring and also of the catch proper, as their inner edges are of burr-like sharpness. Moreover these sloping faces *i*₄ do not afford 20 a good, close fitting abutment for the shank of the catch knob. These sloping faces are removed at the third and fifth working points, shown combined and on a larger scale in Fig. 5, by means of the tapered milling 25 cutters *r* and *s* so that the insertion opening for the clip spring and the clip, formed by the slot *i*, is at the same time widened in funnel-shape corresponding to the shape of the tapered end mills. Owing to this shaping 30 of the slot the finished, inserted catch slides easily without hindrance.

The slot *i*₂ is in itself too narrow for inserting the spring and catch. It is widened at the fourth working point by means of a 35 tapered ram *u*, Fig. 2, so that it receives the shape shown in Fig. 8.

At the last working point the finished worked blank *i* is lifted off the revolving disc *n* by means of the ejector *v*.

40 The finishing of the spring ring is effected by a separate device or by hand in that, after the soldering on of the suspension eye, the catch spring and the catch are inserted and then the walls of the slot *i*₂ returned into 45 their parallel position by compressing the guide sleeve *i*.

I claim:—

1. A process for working guide sleeves for 50 spring rings, consisting in cutting the slot, in which the shank of the catch button runs, by means of a cutter, and in finishing said slot by means of a similar tool the cutting edge of which moves in opposite direction.

2. A process as specified in claim 1, consisting 55 in removing cut faces visible from the outer side formed by the cutting of the slot and the burr-like sharp edges formed on the edges of said faces by means of tapered end mills, and in producing at the same time a 60 funnel-shaped opening for inserting the catch spring and the catch.

In testimony whereof I affix my signature.

BERNHARD FOERSTER.
